UNITED STATES PATENT OFFICE.

WILLIAM C. ANDERSON, OF EAST CAMBRIDGE, MASSACHUSETTS.

DESIGN FOR THE ORNAMENTATION OF GLASSWARE.

SPECIFICATION forming part of Design No. 17,072, dated January 25, 1887.

Application filed November 26, 1886. Serial No. 220,005. Term of patent 7 years.

To all whom it may concern:

Be it known that I, WILLIAM C. ANDERSON, a citizen of the United States, residing at East Cambridge, county of Middlesex, and State of Massachusetts, have invented and produced a new and original Design for the Ornamentation of Glassware for Table Use, of which the following is a specification, reference being had to the accompanying drawing, forming part thereof.

Referring to the drawing, illustrating a glass dish ornamented with my design, *a* represents a star located at the bottom of the dish. Surrounding the star, which is the central figure of the design, and partially entering the space below adjacent points of the stars, are what I denominate "rays," which are lettered *b*. These rays *b* radiate from the inner angles of a series of crossed or overlapped arches, *c c*, 20 the main part of the arches being herein shown as beaded, as at *d*, each arch showing two parallel lines. The arches within their curved tops are provided with a star-like figure, *e*, while outside the tops of the said arch are fan-shaped figures *f*.

The most essential feature of my design, and which imparts to it its chief striking and artistic peculiarity, is the ornamental band composed of the crossing arches, the lines forming 30 the said arches terminating in inwardly-projecting points.

I claim—

1. The design for the ornamentation of glass-

ware herein shown and described, the same consisting of a circular band composed, essentially, of crossing arches presenting double lines, with ornamental star-like figures within the spaces bounded by the said lines, and the latter terminating in inwardly-projecting points.

35

2. The design for the ornamentation of glass-ware herein shown and described, the same consisting of a circular band composed, essentially, of crossing arches presenting double lines, with star-like figures within the spaces 45 bounded by the said lines, and with the rays *b* radiating from the inner angles of the crossed lines of the arches and filling the spaces between the inner ends of the said lines.

40

3. The design for the ornamentation of glass-ware herein shown and described, the same consisting of the central star, *a*, having a star-like figure in its center, and the outer circular band composed, essentially, of the double-lined crossing arches *c*, terminating in inwardly-projecting points, the star-like figures *e* within 50 the said arches, the rays *b* within or between the inner terminations of the said arches, and the fan-like figures outside thereof.

55

In testimony whereof I have signed my name 60 to this specification in the presence of two subscribing witnesses.

WILLIAM C. ANDERSON.
